UNITED STATES PATENT OFFICE

WILLIAM L. EVANS, OF WASHINGTON, INDIANA

DESIGN FOR A GARMENT RACK

Application filed June 18, 1929. Serial No. 31,750. Term of patent 14 years.

To all whom it may concern:

Be it known that I, WILLIAM L. EVANS, a citizen of the United States, residing at Washington, in the county of Daviess and State of Indiana, have invented a new, original, and ornamental Design for a Garment Rack, of which the following is a specification, reference being had to the accompanying drawing, forming part thereof.

In the drawing:

Fig. 1 is a front elevation of a garment rack, showing my new design;

Fig. 2 is a top plan view of the rack; and Fig. 3 is an end view of the rack.

I claim:

The ornamental design for a garment rack, as shown.

In testimony, that I claim the foregoing as my own, I have hereunto affixed my signature.
